CAN

Harry Sebell, Boston, Mass., assignor of one-half
to Arthur H. Parker, Lexington, Mass.

Application June 5, 1933, Serial No. 674,388

1 Claim. (Cl. 220—42)

This invention relates to cans of the type which have a body section and a seamless neck or cover-receiving section secured to the body section with a double lock seam and arranged to 5 form an extension of the body section and thus add to the capacity of the can.

One of the objects of the invention is to provide a novel can of this type in which the lower end of the neck section sets into and has an overlapping relation with the top of the body section thereby adding to the strength of the can at 10 the double lock seam connection.

Another object of the invention is to provide a can of this type in which the portion of the body section immediately below the neck section has the same interior diameter as the neck section and co-operates with the seaming chuck for aligning the body section and neck section during the formation of the double lock seam.

In order to give an understanding of the invention I have illustrated in the drawings a selected embodiment thereof which will now be described after which the novel features will be pointed out in the appended claim.

Fig. 1 is a view showing the neck section of the can in one of its stages of formation;

Fig. 2 is a sectional view showing the neck section ready to be assembled to the body section;

Fig. 3 is a partial sectional view showing the body section ready for assembly with the neck section;

Fig. 4 shows the neck section and body section assembled and illustrates the first step in the forming of the double lock seam connection between the two sections;

Fig. 5 is a partial sectional view showing a completed can embodying my invention with the cover closing the open end of the can.

A can body embodying my invention is formed with the body section 1 and the neck section 2, these two sections being united with the double lock seam indicated generally at 3. The neck section forms an extension of the body section and adds to the capacity of the can.

One feature of the invention relates to a construction wherein the lower end portion 4 of the neck section 2 fits into the upper part 5 of the body section 1 so that at the double lock seam the upper end of the body section and the lower end 45 of the neck section have an overlapping relation.

The neck section is a seamless section and it is formed from sheet metal which is pressed into shape to present the main cylindrical portion of the neck section 2 at the lower end of which the 50 metal is bent back on itself as shown at 4 so that

at said lower end the neck section has a double thickness. This portion of double thickness is that which sets into the upper end 5 of the body section 1.

One way of making the neck section is shown in Figs. 1 and 2. The blank of sheet metal may first be formed into the shape shown in Fig. 1 so as to present the vertical cylindrical seamless portion 6 and the laterally-extending seaming flange 7 which is connected to the vertical portion 6 by 10 the curved portion 8 that is situated below the seaming flange. The two sides of this curved portion 8 may then be folded together as shown in Fig. 2 to present the two ply or double thickness portion 4 below the seaming flange 7.

The body section 1 is made in any suitable or usual way with an outwardly-extending seaming flange 18 at its upper edge. In making the body section 1, however, the upper part 5 thereof is made of the correct size to receive the lower two-ply portion 4 of the neck section 2 so that when the neck section and body section are assembled with their seaming flanges 7, 18 in mating relation as shown in Fig. 4 the portion 4 of the neck section 2 below the seaming flange 7 will fit into the part 5 of the body section 1. With the neck section and body section thus assembled the two seaming flanges are rolled together to form the double lock seam 3. This is done in any suitable way such as by introducing a seaming chuck 9 into 20 the aligned neck section and body section and then acting on the aligned seaming flanges 7, 18 with a seaming roll 10 of any suitable construction. The roll herein shown is similar in construction to that illustrated in my co-pending application, Serial No. 669,127, filed May 3, 1933.

The seaming chuck 9 not only forms a backing for the body section and neck section 1 and 2 during the forming of the double lock seam but it also serves to align the body section and neck section and hold them in alignment while the double lock seam is formed. For this purpose I propose to make the portion of the body section 1 immediately below the neck section 2 of the same diameter 40 as the neck section and to use a seaming chuck 9 which fits the neck section and this portion of the body section.

As herein shown the body section is reduced in diameter immediately below the part 5 as indicated at 11 and the interior diameter of the portion 11 is the same as that of the neck section 2. Hence when the seaming chuck 9 is introduced into the neck section and body section it not only fits the interior of the neck section but also the 50 55

interior of the portion 11 of the body section and this serves to align the two sections 1 and 2 properly for the lock-seaming operation.

The lock seam is formed by rolling the mating 5 seaming flanges 7 and 18 downwardly so that the lock seam itself overlies the overlapping portions of the body section and neck section. This structure strengthens the can at this point and yet provides a can having a seamless neck section which 10 is united to the body section with a double lock seam and which also forms an extension of the body section and adds to the capacity of the can.

12 indicates a cover or closure of the plug type by which the can may be closed, this closure having 15 a tight frictional fit with the seamless neck section 2.

One advantage of a can made in this way is 20 that the neck has an opening of the full diameter of the can and which is free from any shoulders which interfere in any way with draining the contents of the can when the latter is emptied.

Cans of this type are frequently used for packaging paint and it is a common practice for a 25 painter to use the paint directly from the can.

A paint can embodying my invention has the further advantage that it is entirely free from cover-receiving grooves which become filled with

paint during the operation of wiping the brush on the top edge of the can.

A paint can with a seamless neck embodying my invention has a full width opening and will thus accommodate a larger brush than a can of the same size but having the construction now commonly found in paint cans.

I claim:

A can having a body section and a seamless neck section forming an extension of the body section 10 and adding to the capacity of the can, the material forming the side walls of the neck section being bent back on itself with the two plies in contact with each other, said two-ply portion of the neck section fitting into the upper portion of the 15 body section, and said neck section and body section being secured together by two outwardly-extending contacting seaming flanges, one on the neck section and the other on the body section, which are rolled together to produce a double lock 20 seam on the exterior of the can, the lower end of the neck section and the portion of the body section immediately below the neck section having the same diameter and forming together a chuck-engaging surface for engagement with a chuck 25 during the rolling of the seaming flanges to form the double lock seam.

HARRY SEBELL.
